INVENTOR,
John P. A. Pearson,
BY Francis M. Wright;
ATTORNEY

UNITED STATES PATENT OFFICE.

JOHN P. A. PEARSON, OF SAN FRANCISCO, CALIFORNIA.

COMPOUND RAIL.

1,028,635.

Specification of Letters Patent.

Patented June 2, 1914.

Application filed April 24, 1913. Serial No. 763,338.

To all whom it may concern:

Be it known that I, JOHN P. A. PEARSON, a citizen of the United States, residing at San Francisco, in the county of San Francisco and State of California, have invented new and useful Improvements in Compound Rails, of which the following is a specification.

My invention relates to improvements in railway rails.

One object of the invention is to provide means for connecting two rails, the ends of which are adjacent, so that the rolling stock is not allowed to drop in passing from one rail to another, nor are the ends of said rail allowed to be depressed by the movement of the rolling stock thereover.

Another object is to dispense with the use of threaded bolts, screws, nuts, plates and other devices of small size, which it is the present practice to use in railroad construction for holding the ends or parts of rails together, and which so easily rust, loosen, and break, thus requiring continuous repair, and necessitating a continuous cutting up and repairing of streets and roadways.

Another object is to provide a rail construction which will not be injuriously affected by the expansion and contraction due to changes of temperature or by the raising and settlement of the roadbed.

Another object of the invention is to prevent spreading of the rails.

In the accompanying drawing, Figure 1 is a sectional perspective of my improved rail; Figs. 2, 3, 4, 5 and 6 are similar views of portions thereof detached; Figs. 7, 8 and 9 are similar views of modifications of the rail.

Referring to the drawings, 1, 2 indicate body sections, and 3, 4 cap sections of my improved rail. The surfaces along which said sections 1 and 2 are in contact with one another have the following form:—Proceeding downward from the top along a surface 6 making a considerable angle with the vertical, then downward along a surface more nearly vertical, then upward along a surface 8 parallel with the surface 6, then downward along a surface 9 parallel with the surface 7, then upward along a surface 11 parallel with surfaces 6 and 8. Said section 2 thus contains two portions 20 and 25, all the outer surfaces of which slope upwardly, so that the section 2 cannot be removed on the section 1 by a direct trans-

verse horizontal movement, but must be raised therefrom. The lower portion of section 2 is separated from section 1 by a key section 12, which is in contact with the section 2 along a surface 13 extending downwardly from the surface 11 and making an obtuse angle therewith, and along a surface 15 extending upwardly from the outer edge of the surface 13 and making an acute angle 65 therewith. The key section 12 is in contact with the section 1 along a surface 14 extending downward from the surface 11 and parallel with the surface 9, then along a surface 16 extending from the lower edge of 70 the surface 14 and making therewith an angle somewhat greater than the angle between the surfaces 9 and 11, then along a surface 17 parallel with the surface 13, and then along a surface 18 making a very acute 75 angle with the surface 17 and terminating in the horizontal bottom 19 of the section 1, the key section 12 having also a horizontal bottom 21. While the section 2 is in contact with the key section, it does not rest thereon, 80 but its weight is supported by means of lugs 22, (Fig. 3) projecting downwardly from the surface 13 of the section 2 and passing through slots 23, (Fig. 4) longer than the lugs 22, in the key section, the bottom of 85 said lugs resting on the surface 17 of the section 1. The object of this construction is to enable the key section to be slid longitudinally in order to take the rail sections apart. In its normal position, the key section 90 cannot be removed transversely from the rail because of the portions of the key section 12 and the body section 1, which engage along the surface 16. But at suitable intervals said portions are cut away, as 95 shown at 24, (Figs. 2 and 4), so that when the key section is slid longitudinally until the cut away portions of each section register with the portions not cut away of the other section, then the key section can be 100 moved in a direction transverse of the rail through a distance sufficient to permit the corner 26 of the section 2, between the surfaces 13 and 14, to clear a corner 27 between the surface 14 and the outer surface 28 of the 105 key section 12. Then the section 2 and cap section 4 are moved in a direction parallel with the surfaces 6, 8 and 11.

When it is desired to remove the cap sections 3 and 4 from the sections 1 and 2 without separating said sections 1 and 2, this is effected in the following manner. The up-

per surfaces of the sections 1 and 2 are so shaped that, when in position, there is formed a dove-tailed or under-cut longitudinal groove 29 in which the cap sections are held by a depending under-cut rib, of which one-half 31 is formed on the cap section 3 and the other one-half 32 upon the cap section 4. The one-half 31 of the rib is formed on its outer side with recessed portions 33 (Fig. 5) and the corresponding side of the groove is also formed with recessed portions 34 (Fig. 2). When the cap section 3 is slid longitudinally on the section 1, so that its cut-away or recessed portions register respectively with the portions not cut-away of the side of the groove, then the cap section 3 can be raised from off the section 1. The cap section 4 can then be moved transversely in the direction of section 1, and also raised from the section 1.

While I have herein shown removable cap sections, yet in Figs. 7 and 8 I show them formed in one piece with the respective sections 1 and 2.

In Fig. 7 I have shown a modification of the invention in which the key section 12 is omitted. The body section 2 is then in contact with section 1 along a surface 36 extending from the surface 13 at an angle parallel with the surface 11. In this case, for holding said section 2 to the section 1, there are provided locking plates 37 having lips 38 which overhang the sections 1 and 2 adjacent to their line of juncture, said lips having depending longitudinal ribs 39 which enter grooves 41 in the section 2. At suitable intervals said section 2 is formed with cut-away portions 42, which permit said ribs to pass transversely therethrough, when the locking plates are slid longitudinally on the sections 1 and 2. Said plates can then be withdrawn transversely.

I claim:

1. A rail formed of sections, of which one has a longitudinal ribbed portion both sides of which slope upwardly, and the other has a longitudinal recessed portion to receive the ribbed portion of the first-named section, and removable means for preventing upward movement by which the ribbed portion can be removed from the recessed portion.

2. A rail comprising sections each formed of ribbed and recessed portions alternating

longitudinally of the rail, the ribbed portions of the two sections preventing separation therefrom when engaging one another, said sections being separable when the ribbed portion of either section registers with the recessed portion of the other section.

3. A rail comprising body sections and a key section, one of said body sections having a longitudinal ribbed portion with upwardly extending sides, and the other body portion having a longitudinal recess to receive said ribbed portion, said key section having means engaging the first-named body section to prevent upward movement in the direction in which said ribbed portion can be raised from said recessed portion, and said first-named body section and the key section having co-engaging ribbed portions preventing said key section being moved transversely relative to said body section and recessed portions intervening between said ribbed portions permitting said transverse movement when registering with the ribbed portions of the body section.

4. A rail comprising body and cap sections, the body having an undercut longitudinal groove, and the cap sections having longitudinal half ribs, which, when placed together, form a dove-tailed rib engaging said undercut groove to prevent removal of the cap sections from the body.

5. A rail comprising body and cap sections, the body having an undercut longitudinal groove, and the cap sections having longitudinal half ribs, which, when placed together, form a dove-tailed rib engaging said undercut groove to prevent removal of the cap sections from the body, one of said cap sections and the body each having alternate ribbed and recessed portions the ribbed portions of the cap section and the body engaging one another to prevent the removal of the cap section from the body, the cap section being slidable upon the body to permit its ribbed portions to register with the recessed portions of the body to remove the cap section.

In testimony whereof I have hereunto set my hand in the presence of two subscribing witnesses.

JOHN P. A. PEARSON.
